LIFE RAFT

Eugene D. Taylor, Pasadena, Calif.

Application May 7, 1943, Serial No. 485,986

3 Claims. (Cl. 9—11)

This invention relates to life rafts or barges adapted to be carried on marine vessels and discharged or released therefrom when the vessel has been damaged or is in a sinking condition.

An object of the invention is to provide a life raft or barge which is reversible in the sense that the top and bottom of the barge are substantially counterparts of each other. The use of inclined launching platforms and release gears therefor for releasing life rafts and the like is now somewhat conventional. By means of these inclined launching platforms the life raft which is normally carried thereby is released by the release gear and allowed to fall from the vessel into the water, it being contemplated that survivors will jump from the vessel into the water, swim to the life raft, and board it. By having the life raft or barge reversible, that is with top and bottom counterparts of each other, it is immaterial whether the barge lands in the water right side up or upside down, the uppermost side affording all of the facilities that the barge provides.

A further object of the invention is to provide a life raft on the top and bottom of which there are cockpits and around which cockpits are arranged decks that afford seating surfaces for survivors boarding the barge. The bottom surface of the uppermost cockpit being disposed above the normal water line and to provide means for draining the uppermost cockpit thus avoiding any necessity of bailing.

Still another object of the invention is to provide a life raft or barge having cockpits provided at the top and bottom thereof so that whichever is uppermost is available and to provide a reservoir for water and stores between the cockpits accessible from either cockpit so that the reservoir may be opened from whichever cockpit is uppermost.

A further object of the invention is to provide a reversible life raft or barge wherein certain accessories, such as oars, masts, booms, sails, a canopy, and strakes therefor are releasably mounted on the sides of the barge between the top and bottom thereof so as to be available for use regardless of which cockpit is disposed uppermost when the barge is discharged from the launching platform into the water.

Another object of the invention is to provide an improved construction of life raft or barge with solid decks and sides and with cockpits on the top and bottom thereof constructed of a multiplicity of segments of light porous wood, such as balsa wood, and protected by a waterproof outer skin wherein each segment of balsa

wood is coated with waterproof glue in the course of the assembly so that should any segment become damaged or punctured such segment while it may become water-logged will not affect remaining unpunctured segments which retain the original buoyancy.

With the foregoing and other objects in view, which will be made manifest in the following detailed description and specifically pointed out in the appended claims, reference is had to the accompanying drawings for an illustrative embodiment of the invention, wherein:

Fig. 1 is a view in side elevation of a life raft or barge embodying the present invention illustrating it in floating position and as having its canopy erected thereon, the canopy being illustrated in dotted lines;

Fig. 2 is a top plan view of the barge, the canopy being shown as having been removed;

Fig. 3 is a view in vertical section taken substantially upon the line 3—3 upon Fig. 1 in the direction indicated, illustrating the manner in which the strakes of the canopy are erected;

Fig. 4 is a view in front elevation of the barge illustrating two masts and sails as having been erected thereon; and

Fig. 5 is a view in side elevation of the barge in the condition illustrated in Fig. 4.

Referring to the accompanying drawings wherein similar reference characters designate similar parts throughout, the improved life raft or barge is made up of a plurality of individual segments or pieces of light, porous, highly buoyant wood indicated at 10. Balsa wood is preferable for this purpose although other similar highly buoyant wood may be employed.

In making up the body of the barge each of the segments has waterproof glue applied thereto and is assembled together with other segments following which the glue is allowed to set and dry. Usually the glue is applied to opposed faces of adjoining segments and when it dries it forms a water-resistant coating around each segment. The sides and decks are preferably covered with a layer of waterproof plywood forming an additional exterior protection.

As is indicated on Fig. 3, it is preferable to arrange the segments in such a manner that some segments will have their grain extending longitudinally or horizontally and other segments will have their grain running transversely or vertically.

The body of the barge is so formed as to be reversible. That is, it has a flat top and bottom within which there is formed upper and lower

cockpits 11 and 12. In the preferred form of construction the exterior surface of the barge as well as the interior of each of the cockpits is faced with waterproof plywood indicated at 13.

As will be observed from a comparison of Figs. 1 and 2, the top and bottom of the barge are preferably rectangular in shape and the cockpits are likewise preferably rectangular in shape, whereas the sides are preferably in the form of a parallelogram. With this arrangement it will be appreciated that the body of the barge is symmetrical in most respects about a horizontal central plane. Consequently, when the barge embodying the present invention is released from a launching platform on a vessel and is allowed to drop into the water, it is immaterial which side of the barge is uppermost when the barge lands on the water. For example, if cockpit 11 is uppermost, this cockpit may be used by survivors. On the other hand, if during the launching the barge should be turned so that cockpit 12 is uppermost, then this cockpit may be used by survivors.

Vertical tie bolts 14 having ring or eye heads extend through the barge from top to bottom thereof and assist in holding the body of the barge together. Similarly, transverse tie bolts 15 may extend transversely through the barge through the floor or partition 16 that separates the cockpits. Corners of the body of the barge may be provided by somewhat heavier wood, such as for example oak, and facing pieces 17 and 18 which extend fore and aft at the edges of the barge may be formed of wood, such as Douglas fir. The facing pieces 17 and 18 that extend fore and aft project slightly beyond transverse bow and stern facing pieces 18 and 19 so that the edges of the facing pieces may serve as runners in supporting the barge on the rails of the launching platform and the facing pieces 18 and 19 will not hinder release of the barge therefrom.

A rub rail 20 also extends longitudinally of the barge on each side thereof at the approximate water line. Such rub rail may be formed of any durable wood, such as for example oak. In the partition 16 that separates the two compartments 11 and 12, there is provided a reservoir 21 preferably divided into a plurality of compartments. One compartment may be filled with fresh water. Another compartment may be filled with food, and the third compartment with other necessities, such as for example, rockets. Each compartment is equipped with a closure, the closures being indicated at 22 at the top as well as at the bottom of the compartment so that regardless of the position assumed by the barge when launched, access to the compartments is available from that cockpit which happens to be uppermost.

A drain pipe 23 leads from each compartment through the body of the barge to the end thereof, such drain pipe may be controlled by a sea cock or plug 24. This enables draining of the uppermost compartment should it become filled or partially filled with water. Inasmuch as the bottom of the uppermost compartment is above the water line, bailing of the uppermost compartment is unnecessary. Normally, these sea cocks are left open and an additional advantage is gained thereby. If the barge happens to land when launched with the lower cockpit 12 lowermost, it will be appreciated that a certain volume of air is entrapped therein. This air being compressible to a certain extent tends to cushion the fall of the barge onto the water, the air escaping

through the lowermost drain pipe 23. Thus, while there is an initial cushioning effect, the air is allowed to escape allowing the barge to sink in the water to the desired depth reducing danger of overturning. If desired scupper openings 5 may be formed through the face pieces 17 and 18 to also allow or provide for the escape of air.

A life line 24 which may be equipped with floats 25 may be secured at spaced intervals along 10 the rub rail to facilitate survivors climbing onto the rub rail immediately above the rub rail there are releasably secured oars 26, masts and booms, and the strakes 27 of a canopy. The sails and the canopy may also 15 be folded and stored at this locality. Straps or ties 28 may maintain these accessories at this location. Oarlocks 29 may be permanently attached adjacent the facings 17 and 18 such as by chains or cords and sockets are formed in 20 these facings to receive the oarlocks. Sockets 30 are also formed in the facings to receive the lower ends of the strakes 27 which are in the form of bendable hickory rods adapted to be connected together over the center of the raft such 25 as by a sleeve 31. The canopy 32 which may be formed of canvas is cut so as to suitably fit over the strakes to completely cover the top of the barge in the event of bad weather. At the forward end of whichever surface or deck happens 30 to be uppermost there is hingedly secured a splash board 33 which may be swung upwardly and braced as by a brace 34. Cords or ropes 35 may connect the forward portion or hood of the canopy to the splash board. Sockets 36 are arranged 35 adjacent the forward corners of the barge in which may be strapped masts 37 on which may be mounted the booms 38. The sails 39 are preferably attached to the masts and booms, such as by lacing, and backstays 40 may connect the 40 masts with the eye or rings of the rear tie bolts 14.

Inasmuch as the barge is symmetrical with respect to a central horizontal plane, it will be appreciated that when discharge into the water 45 from the launching platform it is immaterial which side of the barge is uppermost. Survivors may swim to the barge, grasp the life line 24, and pull themselves into the upper cockpit surrounding which there is the top surface or deck 50 which affords an adequate seating area. The equipment fastened onto the sides of the barge as by the ties or straps 28, can be removed and released and taken into the barge and deposited in the uppermost cockpit regardless of which 55 cockpit is uppermost on launching.

Water and food are available through the closures 22 which happen to be uppermost and in the event of bad weather the strakes 27 and the canopy may be erected. In the event of good 60 weather and a favorable breeze, the canopy may be taken down and the masts and sails erected.

While no attempt is made to design the barge to be readily maneuverable while under sail, it will move quite readily in running before the 65 wind. If the barge is constructed in approximately the proportions illustrated with the area of the top deck approximately 10' 6" x 7' and the height of the barge from deck to deck 36", I find that the barge is capable of seating twenty- 70 two persons with approximately 14" freeboard, thus affording dry seats and a dry upper cockpit. As indicated upon the drawings the reservoir 21 preferably extends above and below the partition 16 some considerable distance, thus providing 75 adequate interior space and also providing

seats for passengers or survivors in addition to the deck space. Preferably the water compartment has a large closure or deck plate 22a and a smaller closure 22b arranged adjacent the upper corner thereof when the barge is mounted in an inclined position on the conventional release gear. The small closure on the upper side of the barge can be removed periodically to permit of water inspection from time to time and the corresponding small closure on the under-side of the barge can be removed when occasion requires to drain the water compartment and permit its being refilled, it being understood that the closure on the under side corresponding to the closure 22b would be located at or near the bottom of the water compartment when the barge is supported in an inclined position on the release gear.

It will be noted that the raft or barge herein disclosed has identical top and bottom construction with parallelogram sides with solid, deck and side, cockpits arranged on the top and bottom.

Various changes may be made in the details of construction without departing from the spirit or scope of the invention as defined by the appended claims.

I claim:

1. A life raft composed of upright and horizontal sections of sealed balsa wood, cockpits formed in the raft on the top and bottom thereof and tie rods extending through the sections of balsa wood transversely of the raft in front of and behind said cockpits.

10 2. A life raft composed of upright and longitudinally extending horizontal sections of balsa wood, a plywood covering on the exterior surface of the raft, cockpits formed in the top and bottom surfaces of the raft, and tie rods extending across the raft before and behind each of the cockpits.

15 3. A life raft composed of upright and longitudinally extending horizontal sections of balsa wood, a plywood covering on the exterior surface of the raft, cockpits formed in the top and bottom surfaces of the raft, and tie rods extending across the raft before and behind each of the cockpits, vertical tie rods extending from top to bottom of the raft at the sides of the cockpits.
